UNITED STATES PATENT OFFICE

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN

INTERNAL-COMBUSTION ENGINE

Application filed May 28, 1926. Serial No. 112,365.

This invention relates to internal combustion engines, and more particularly to means for lubricating the piston cylinders of said engine.

It is common in the internal combustion engine art to lubricate the cylinders by means operating only when the engine is working.

The object of the present invention is to provide means for lubricating the cylinder bores during the cranking of the engine, just preliminary to the starting of the engine proper. With this object in view, the invention consists of means for supplying the cylinder bores with a lubricant, preferably oil from the sump of the engine, which means are operated by the cranking mechanism, such for example as the electric starting motor. Any suitable means operated by the starting motor for directly ejecting a lubricant into the cylinder bores through their open lower ends may be employed. Preferably, a series of paddles is mounted on a horizontal shaft in the sump of the engine and so located and rotated at such speed that the oil in the sump, even when very cold, will be copiously supplied directly to the cylinder bores and generously lubricate the same during the cranking period.

The inventive idea is capable of receiving a variety of mechanical expressions, one of which, for the purpose of illustrating the invention, is shown in the accompanying drawings, but it will be expressly understood that such drawings are for purposes of illustration only and are not intended to define the limits of the invention, reference being had to the appended claims for such purpose.

In said drawings—

Fig. 1 is a vertical cross-section of an internal combustion engine through one of the cylinders and the sump; and

Fig. 2 is a broken detail perspective showing the application of the invention.

In said drawings, 1 is the engine cylinder, 2 the piston, and 3 the sump containing lubricating oil. 4 is the usual or any suitable electrical starting motor, and 5 is the rear end of the armature shaft of said starting motor. A shaft 6 is mounted longitudinally of the sump and, as here shown, above the surface of the

oil therein, said shaft being provided with a plurality of paddles 7 of any suitable construction and of such proportions as to extend downwardly and, during the revolutions of the shaft, take up and throw the oil into the cylinders 1. For the purpose of revolving the shaft 6, the same is operatively connected by any suitable means with the armature shaft 5 of the electric self-starter 4. As here shown, said means consist of a shaft 8 suitably geared at 9 to the armature shaft 5 of the starting motor and at 10 to the paddle shaft 6. Preferably, the shaft 6 extends throughout the length of the sump 3, and a sufficient number of paddles are supplied thereto to effectively lubricate a series of cylinders of any desired number arranged above the sump.

The operation of the mechanism will be readily understood. When the starting motor is set in motion, the shaft 6 is rapidly revolved and the oil, even though the same may be very cold, is copiously supplied to the cylinders through their open lower ends, so that they are efficiently lubricated, and when the cranking motor 4 is stopped the operation of the shaft and its paddles ceases, and the cylinders are lubricated in the usual way by the ordinary lubricating mechanism of the engine.

What is claimed is—

1. In an internal combustion engine, the combination of a piston cylinder, an oil sump located beneath the cylinder, an electric starting motor, and means operated by the starting motor for supplying oil directly from the sump to the piston cylinder, through the open lower ends thereof.

2. In an internal combustion engine, the combination of a piston cylinder, an oil sump beneath the same, a starting motor for said engine, a shaft in said sump, means operatively connecting said shaft to the starting motor, and means actuated by said shaft for throwing oil into the cylinder, through the lower open end.

3. In an internal combustion engine, the combination of a cylinder, an oil sump beneath the same, a starting motor, a shaft

in the sump, paddles on said shaft which enter the oil in the sump when the shaft is revolved, and operative connections between the armature shaft of the starting motor and the paddle shaft in the sump.

5 In testimony whereof I have signed this specification.

JESSE G. VINCENT.
